UNITED STATES PATENT OFFICE.

L. SOLON GROUT, OF CHICAGO, ILLINOIS.

DESIGN FOR A SIGN FOR TEA DEALERS.

SPECIFICATION forming part of Design No. 12,594, dated December 13, 1881.

Application filed November 4, 1881. Term of patent 3½ years.

To all whom it may concern:

Be it known that I, L. SOLON GROUT, a citizen of the United States, residing at Chicago, in the county of Cook and State of Illinois, 5 have invented and produced a new and original Design for a Sign for Tea Dealers; and I do hereby declare that the following is a full, clear, and exact description thereof, reference being had to the accompanying drawing, which 10 forms a part of this specification.

The drawing represents an elevation of one side of my sign for tea dealers.

The leading feature of the design consists in a sign made to represent the image of a Chinaman, who holds his arms spread out horizontally, so as to imitate in outline the Roman capital letter T. This Chinaman, thus represented in his native dress with highly ornamental trimmings, may have painted horizontally 15 upon his arms and vertically upon his dress, in fancy letters, the word "Teas," or names of other merchandise; and a loop to his

head, by which to hang the sign, may be shaped and painted to represent the Chinaman's cue curled upward.

This sign may be made of wood or metal, or of a combination of both, in any suitable manner, and is to be tastefully finished in colors and gold-leaf, and so as to have the same appearance from either side.

What I claim is—

The design for a sign for tea dealers, consisting of the image of a Chinaman holding his arms out horizontally, so as to represent in outline the Roman capital letter T, substantially 25 30 35 as described and shown.

In testimony that I claim the foregoing as my invention I affix my signature in presence of two witnesses.

L. SOLON GROUT.
